UNITED STATES PATENT OFFICE.

JOHN H. M. DUDLEY, OF NEW YORK, N. Y., ASSIGNOR TO ROLFE & MADDOCK, OF NEW YORK, N. Y., A COPARTNERSHIP CONSISTING OF B. A. ROLFE AND C. B. MADDOCK.

THEATRICAL APPLIANCE.

1,230,877.

Specification of Letters Patent. Patented June 26, 1917.

Application filed September 29, 1916. Serial No. 122,807.

To all whom it may concern:

Be it known that I, JOHN H. M. DUDLEY, a citizen of the United States, residing at New York, in the county and State of New York, have made a certain new and useful Invention in Theatrical Appliances, of which the following is a specification.

This invention relates to theatrical appliances, and particularly to appliances of this nature adapted to produce novel illusionary effects upon the entertainment stage.

The general object of the invention is to provide means for reproducing life size portions of buildings, vessels or the like upon the theatrical stage and more particularly to provide means for reproducing the fore-deck of a battleship, with the turret guns thereof projecting over the heads of the audience.

Further objects of the invention will appear more fully hereinafter.

The invention consists substantially in the construction, combination, location and relative arrangement of parts, all as will be more fully hereinafter set forth, as shown by the accompanying drawing, and finally pointed out by the appended claims.

Referring to the drawing,—

Figure 1 is a plan view of a stage arranged and equipped with apparatus and embodying my invention.

Fig. 2 is a front elevation view of the same.

Fig. 3 is a broken detail sectional view of a portion of the apparatus shown in the foregoing views.

The same part is designated by the same reference numerals wherever it occurs throughout the several views.

It is among the special purposes of my present invention to so arrange the stage settings, scenery, and the like, to give a full size reproduction of a portion of a large building, ship or the like, so that the audience will be looking at such reproduction at a perspective angle. In the concrete illustration I have selected as illustrative of the principles of my invention, I depict the foredeck of a battleship and employ suitable wings, scenic and back drops so arranged as to give the impression to a spectator that he is also on the deck of the vessel and looking down the same. The guns of the forward turret of the war ship, to fulfil the above effect, must necessarily be

so made, or the supporting turret therefor must be so made as to allow the guns to be swung out over the heads of the audience.

In the drawings I show the stage indicated at 1 provided with the usual curtain which is adapted to fall as indicated at 2 in dotted lines in Fig. 1, immediately before the usual tormentors 3. Positioned on the stage 1, and preferably to the right of the center thereof, I place the fore turret which is made preferably of wood frame work and comprises the stationary portion 4 and the gun carrying portion 5, rotatively movable relative to the portion 4. The portion 5 of the turret has protruding from the front thereof guns 6. In this instance three of such guns are employed.

In the right rear corner of the stage a set piece 7 is located depicting the front of the secondary turret from which protrude guns 8, of full size. These guns are directed at an acute angle with the plane of the front of the stage. A curtain, scene panel or drop 9 is placed immediately behind the set piece 7, and is cut out to form the fore mast of the battle ship, and behind this is placed a similar curtain, scene panel or drop 10 cut out and painted to depict the funnel or smoke stack of the battleship. On the part 11 of the rear curtain or drop 12, is painted the rear mast or tower of the ship, all as shown in Fig. 2. It will be understood that the relative sizes of the masts 9, 11 and smoke stack 10 decrease in accordance with the perspective view desired. The remaining portion of the back drop or curtain 12 has painted thereon the usual sea or ocean scene, with horizon, waves, sky and, if desired, similar ships in the distance.

To more clearly bring out the illusion of a sea or ocean scene, wings 13 and 14 cut out to form waves, and having the billows painted thereon may be employed as shown. In front of the wave wings 13, 14, I provide a wing 15, having a rail painted thereon or a complete rail 16 to form the deck rail of the battleship.

From the foregoing it will be seen that the stage proper, being completely bared, and being usually formed of wood strips, as in the case of ordinary wooden flooring, gives the complete impression, being enclosed by the rail 16, of being the foredeck of a battleship.

It is obvious that the guns 6 are too large

to be placed on the stage pointing in their normal position, and on this account I provide the rotary turret portion 5 with a shaft 20 extending through the portion 4, and supported by suitable bearings 21 to allow the free rotation of the portion 5 relative to the portion 4. Any suitable means may be employed to rotate the portion 5, for example, a handle 23 carried by the shaft 20.

10 I will briefly describe how I propose to produce the desired illusionary effect. The stage is set as above set forth, and the swinging turret 4, 5, is placed in the position indicated in dotted lines, Fig. 1. The 15 front curtain 2 is then raised while all of the lights in the theater are out and the turret 5 is then swung by the operator within the same into its normal position with its guns 6 in alinement with the guns 20 8 of the set piece 7. The lights are then turned on the stage, and the effect of the audience being on the foredeck of a battleship, and looking in the direction of its diagonal length, is complete.

25 It will be understood that many changes in details will readily occur to those skilled in the art without departing from the broad scope of my invention as defined in the claims. Therefore, what I claim as new and 30 useful, and of my own invention, and desire to secure by Letters Patent, is,—

35 1. A stage effect or setting comprising in combination a series of scenic wings, simulating a marine perspective, scenic panels simulating portions of a vessel, a turret setting having simulated great guns associated with the scenic panels, and a movable turret disposed below and in front of the fixed turret and having simulated guns, and 40 means for moving said turret, the whole producing the effect of the foredeck of a battleship on the ocean.

2. A stage effect or setting comprising in combination a series of scenic wings, simu-

lating a marine perspective, scenic panels 45 simulating portions of a vessel, a setting having simulated great gun equipment disposed in front of said scenic panels, and a setting disposed below and in front of said first mentioned setting and also having simulated great guns, and means for moving the simulated guns of one setting relative to the simulated guns of the other of said settings.

3. A stage effect or setting comprising in 55 combination a series of scenic wings, simulating a marine perspective, scenic panels simulating portions of a vessel, a setting having simulated great gun equipment disposed in front of said scenic panels, and a 60 setting disposed below and in front of said first mentioned setting and also having simulated great guns, and means for moving the simulated guns of said last mentioned setting over the stage edge and the heads of 65 the audience into alinement with the simulated guns of said first mentioned setting.

4. A stage effect or setting comprising in combination a series of scenic wings, panels and a back drop and stationary settings to 70 simulate the perspective of a complete structure, and a setting adapted to be swung out from the stage relative to said stationary settings, for completing the perspective effect of said structure, and means for swinging said last named setting out from the stage.

5. A stage effect or setting comprising in combination a series of scenic wings, simulating a marine perspective, a turret setting 80 having simulated great guns associated with said wings, and means for revolving said turret relative to said wings.

In testimony whereof I have hereunto set my hand on this 27th day of September 85 A. D., 1916.

JOHN H. M. DUDLEY.
